ATTORNEY.

UNITED STATES PATENT OFFICE

BYRON A. MCANSH, OF CHICAGO, ILLINOIS

REFILLABLE FUSE PLUG

Application filed July 21, 1932. Serial No. 623,751.

This invention relates to electrical safety fuse appliances of the renewable fuse type, and more especially to that form of the same in which an indicating plug is automatically released on a blowing or breakage of the fuse member or strip. And this improvement has for its object:

To provide a structural formation and combination of parts and features in the above mentioned type of fuse plugs, whereby the ready and effective insertions of the fuse strip in a renewable operation is attained, and with which an efficient electrical contact at the respective ends of the fuse strip is also attained, with a ready release and "drop out" of the portions of a blown fuse strip on a separation of the two component members of the sectional enclosing housing of the appliance.

To provide a construction of parts wherein an indicating plug normally retained within the plug housing by the fuse strip, is released on a fusing or "blowing" of the fuse strip, and moves out of the housing to give a visible or like apparent indication of the changed condition of the fuse strip, all as will hereinafter more fully appear.

In the accompanying drawing:

Fig. 1 is a central sectional elevation illustrating the preferred form of this invention.

Fig. 2 is a horizontal section on line 2—2, Fig. 1.

Fig. 3 is a detail side elevation of one of the end contact members of the appliance.

Fig. 4 is an elevation of a type of fuse strip adapted for use in the present structure.

Fig. 5 is a sectional elevation of a simple type or modification of the construction shown in Fig. 1.

Like reference numerals indicate like parts in the several views.

In this invention the main and outer member 1 of the enclosing housing of the appliance is formed of a suitable non-conducting material, having a central bore that is open at one end for the introduction and reception of the hereinafter described removable inner member of the appliance. Said outer member 1 is provided with the usual

fixed outer spirally grooved metal shell 2, which provides an attaching means for the appliance and a terminal or end of the electrical supply system in which the appliance is placed. In this invention the aforesaid outer shell 2, is provided with an inwardly extending flange 2 covering an end of the outer member 1 of the housing, and adapted for electrical conducting contact with the hereinafter described adjacent contact member of the appliance.

In the construction shown, the outer housing member 1 is provided with a cap member or portion 3 to provide a closure for each housing end and at the same time enclose and guide the hereinafter described contact member that has engagement with the fuse strip of the appliance and in addition carries the indicating plug of the appliance.

The removable inner member of the appliance comprises a central stem 4 of the detail construction hereinafter described and an enlarged end portion of a detail construction as follows:

A head or plug 5 of non-conducting material of a size adapted to form a closure for an open end of the bore or cavity of the outer housing 1; a contact disk or ring 6 of metal at one end of the head or plug 5; a manipulating disk 7 of non-conducting material in contact with the ring 6, and having a larger diameter than said contact ring, with a view to safety, and a contact button or disk 8 on the exposed face of the manipulating disk 7 and electrically connected to the contact disk or ring 6 to constitute the central terminal contact of the appliance, and as usual in the present form of fuse and like plugs now in general use.

The central stem 4 of the removable member above referred to comprises a tubular stem of non-conducting material that is yieldingly moved in a longitudinal direction in the appliance, by an expansion spring 9 abutting at one end against a bearing flange 10 in the bore of the stem, and at the other end a like bearing in a recess in the above described closure head 5, of the inner removable member of the appliance.

Guidance of the aforesaid central stem 4,

in a longitudinal direction in the appliance is attained by an axially arranged rod 11 having at one end a stop flange or collar 12 to limit the extent of longitudinal movement 5 of the stem 4, while at its other end said rod is fixedly attached to the aforesaid head or plug 5 and in the construction shown passes through and attaches together the contact disk 6, and manipulating disk 7 and 10 the contact button 8, to provide electrical connection between the contact disk 6 and the terminal button 8, aforesaid.

The companion terminal contact member of the contact structure just described, comprises in the preferred form of the invention shown in Figs. 1 and 3, a head or block 13 of metal or like electrical conducting material adapted for limited longitudinal movement, partly in the bore of the outer housing member 1 and partly in the inner chamber of the cap piece or member 3 and having a marginal end flange 14 for electrical contact with the aforesaid inwardly extending flange 2' of the metal enclosing shell of the outer housing member 1, and preferably through an interposed spring 15 of a similar form, adapted to maintain continued electrical connection between the parts regardless of a limited movement of the head 13 away from 25 the shell flange 2 which may take place in an assembly of the fuse parts. In the construction shown in Fig. 1 the main portion of said terminal contact member or head 13 is formed with a central flared recess or 30 cavity 16 adapted to receive an end of the fuse strip 17, and have conducting contact therewith, with such contact positively and effectively maintained by the free end portion of the stem 4 aforesaid entering said 35 recess or cavity 16 and forcibly holding the end of the fuse strip 17 against the flared wall of said recess or cavity without the necessity of the usual additional means usual to fuse plugs of the present type.

40 At its other end the fuse strip 17 will have lateral flange or bend 17' adapted for bearing against an end of the non-conducting main body and in electrical contact with the conducting disk or ring 6 of the removable 45 member of the fuse plug, when said member is in place.

In effecting an assembly of the parts shown in Fig. 1, the main member 1, free from the removable member, and with movable contact 50 head 13 and its plug 18 pushed inwardly, is adapted to receive a fuse strip 17, which is dropped into bore or cavity, with one end thereof resting in the flared cavity 16 of the contact head 13 aforesaid and the other end 55 of the fuse strip resting against an end of the main member 1. The removable member of the plug is then inserted in the bore of the main member to effect through its central stem 4, the above mentioned holding an electrical contact engagement of an end of the

60 fuse strip with the contact head 13 aforesaid. At the same time a like effective holding and electrical contact engagement of the other end of the fuse strip with the contact disk or ring 6 is attained with the removable 65 member of the plug moved fully into place.

Extending from the aforesaid movable contact member 13, a centrally arranged plug or stud 18, preferably of non-conducting material, has movement in a central orifice 70 in the cap piece 3 of the main member 1, with the end of said plug in a plane with the end or top face of said cap in a normal condition of the appliance, in that the contact head 13, is maintained in such normal contact with the terminal flange 3' of the outer member 1, by the fuse strip action as a holding means against the tendency of said contact head to move away from its electrical contact under the associated spring connection theretofore 80 described.

With a "blowing" or parting of the fuse strip under an excessive electrical load, the aforesaid indicator plug 18 has an outward movement to provide a visible or palpable indication of the fact that the fuse plug is in an inoperative or "blown" condition. Such indicating movement of plug 18, takes place, as the fuse strip 17 releases its holding action on the spring of the renewable member of the appliance, to permit said spring to move the stem 4, and contact head 13 carrying said indicating plug longitudinally and effect the described exposure of the indicating plug.

90 In the modified construction illustrated in Fig. 5, the indicating plug 18 and movable contact head 13, are omitted and contact between one end of the fuse strip 17, with the enclosing metallic shell 2 of the outer housing 95 1 as attained by a central annular flange 2' of the shell 2, with the central stem 4 of the removable member of the fuse plug having fixed attachment to the head or block 5 that is in fixed association with the contact disk or ring 6, manipulating disk 7 and terminal button 8, that forms the terminal connection for the other end of the fuse strip, as in the preferred construction heretofore described.

100 Having thus fully described my invention what I claim and desire to secure by Letters Patent is:—

1. A fuse plug comprising a main housing of non-conducting material formed with a central cavity open at one end and having an outer shell of conducting material provided with a flange extending into said cavity at a point remote from the open end of the same to constitute one electrical terminal of the plug, a removable head of non-conducting material fitting the open end of the aforesaid cavity and provided with a circular contact member adapted in connection with an end of the main housing to secure by holding contact an end portion of a fuse strip, 110 115 120 125 130

with a central terminal button electrically connected with said contact member, and with a central stem of non-conducting material the free end of which has adjacent relation 5 to the aforesaid terminal flange of the outer shell and adapted to secure by holding contact, the other end of the fuse strip in contact with said terminal flange.

2. A fuse plug comprising a main housing 10 of non-conducting material formed with a central cavity open at one end and having an outer shell of conducting material provided with a flange extending into said cavity at a point remote from the open end of the same to constitute one electrical terminal 15 of the plug, a removable head of non-conducting material, fitting the open end of the aforesaid cavity, a disk of non-conducting material carried on an end of the said head 20 and having on one face a circular contact member of less diameter than said disk and adapted in connection with an end of the main housing to secure by holding contact an end portion of a fuse strip, and on its 25 other face a terminal button electrically connected to said contact member, a central stem of non-conducting material on said renewable head, the free end of said stem having adjacent relation to the terminal flange of the 30 outer shell and adapted to secure by holding the other end of the fuse strip in contact with said terminal flange.

3. A fuse plug comprising, a main housing 35 of non-conducting material formed with a central cavity open at one end and having an outer shell of conducting material provided with a flange extending into said cavity at a point remote from the open end of the same to constitute one electrical terminal 40 of the plug, a contact head movable longitudinally in the cavity of the main housing and formed with flared recess in one face, a removable head of non-conducting material fitting the open end of the aforesaid cavity 45 and provided with a circular contact member adapted in connection with an end of the main housing to secure holding contact an end portion of a fuse strip, with a central terminal button electrically connected to said contact member, and with a central stem of 50 non-conducting material, having a longitudinal tendency under the influence of a spring, with its free end in adjacent relation to the recess of the aforesaid sliding contact head and adapted to secure by holding contact the other end of the fuse strip in said recess.

4. A fuse plug comprising, a main housing 55 of non-conducting material formed with a central cavity open at one end and having an outer shell of conducting material provided with a flange extending into said cavity at a point remote from the open end of the same to constitute one electrical terminal of the plug, a contact head movable longitudinally in the cavity of the main housing 60 and interposed spring tend-

and formed with a flared recess in one face and carrying on its other face an indicator plug extending out through an orifice in the main housing, a removable head of non-conducting material fitting the end of the aforesaid cavity and provided with a circular contact member adapted in connection with an end of the outer housing to secure by holding contact an end portion of a fuse strip, with a central terminal button electrically connected to said contact member and with a central contact stem of non-conducting material having a longitudinal tendency under the influence of a spring with its free end in adjacent relation to the recess of the aforesaid sliding contact head and adapted to secure by holding contact the other end of the fuse strip in said recess.

5. A fuse plug comprising, a main housing 75 of non-conducting material formed with a central cavity open at one end and having an outer shell of conducting material provided with a flange extending into said cavity at a point remote from the open end of the same to constitute one electrical terminal of the plug, a contact head movable longitudinally in the cavity of the main housing and formed with a flared recess in one face, a spring member of conducting material interposed between said contact head and the flange of the outer shell, a removable head of non-conducting material fitting the open end of the cavity of the main housing and provided with a circular contact member 80 adapted in connection with an end of said housing to secure by holding contact an end portion of a fuse strip, with a central terminal button electrically connected to said circular contact member, and with a central stem of non-conducting material having a longitudinal tendency under the influence of a spring, with its free end in adjacent relation to the recess of the aforesaid sliding contact head and adapted to secure by holding contact the other end of the fuse strip in said recess.

6. A fuse plug comprising, a main housing 85 of non-conducting material formed with a central cavity open at one end and having an outer shell of conducting material provided with a flange extending into said cavity at a point remote from the open end of the same to constitute one electrical terminal of the plug, a contact head movable longitudinally in the cavity of the main housing and formed with a flared recess in one face, a removable head of non-conducting material fitting the open end of the cavity of the main housing and provided with a circular contact member adapted on connection with an end of the main housing to secure by holding contact an end portion of a fuse strip, with a central terminal button electrically connected to said contact member, and with a central stem of non-conducting material formed in 90 slideable sections, and interposed spring tend-

ing to force said section apart longitudinally, the upper end of said stem having adjacent relation to the recess of the aforesaid sliding contact head and adapted to secure by holding contact the other end of the fuse strip in said recess.

7. A fuse plug comprising, a main housing of non-conducting material formed with a central cavity open at one end and having an outer shell of conducting material provided with a flange extending into said cavity at a point remote from the open end of the same to constitute one electrical terminal of the plug, a contact head movable longitudinally in the cavity of the main housing and formed with a flared recess in one face, and carrying on its other face an indicator plug extending out through an orifice in the main housing, a removable head of non-conducting material fitting the open end of the cavity

of the main housing and provided with a circular contact member adapted in connection with an end of the main housing to secure by holding contact an end portion of a fuse plug, with a central terminal button electrically connected to the circular contact member, and with a central stem formed by a longitudinally sliding sleeve of non-conducting material a guide stem fixedly secured to the aforesaid removable head, and an interposed spring tending to force said sleeve away from said head, the upper end of said sleeve having adjacent relation to the recess of the aforesaid sliding contact head and adapted to secure by holding contact the other end of a fuse strip in said recess.

In testimony whereof I hereunto affix my signature.
